UNITED STATES PATENT OFFICE.

RALPH W. EMERSON, OF ROCKFORD, ILLINOIS.

DESIGN FOR A FILE-CASE.

SPECIFICATION forming part of Design No. 22,397, dated May 2, 1893.

Application filed February 18, 1893. Serial No. 462,919. Term of patent 3½ years.

To all whom it may concern:

Be it known that I, RALPH W. EMERSON, a citizen of the United States, residing at Rockford, county of Winnebago, and State of Illinois, have invented and produced a new and original Design for File-Cases, of which the following is a specification, reference being had to the accompanying drawings.

Figure 1, is perspective view of the case in its closed position. Fig. 2, is a perspective view of the same in its open position.

The leading features are the vertical sides 1 having the forward edge near the top inclined as shown at 2; the top 3 having rounded edges; the base 4 having the edges rounded

and projecting beyond the surfaces of the sides; and the shelf 5 having its edges rounded and like the base, projecting beyond the surface of the side. The sides are fitted with partitions 6 to form suitable file compartments and is provided with a drawer 7 and a rolling top 8.

What I claim is—

The design for file cases herein shown and described.

RALPH W. EMERSON.
